UNITED STATES PATENT OFFICE.

BIRD M. HARDIN, OF BIVINS, TEXAS.

DESIGN FOR AN AUTOMOBILE.

54,086.

Specification for Design.

Patented Nov. 4, 1919.

Application filed May 28, 1919. Serial No. 300,491. Term of patent 14 years.

To all whom it may concern:

Be it known that I, BIRD M. HARDIN, a citizen of the United States, residing at Bivins, in the county of Cass and State of Texas, have invented a new, original, and ornamental Design for an Automobile, of which the following is a specification, reference being had to the accompanying drawing, forming part thereof.

The figure is a side elevation of an automobile embodying my design.

I claim:

The ornamental design for an automobile, as shown.

BIRD M. HARDIN.

Witnesses:

J. B. HARDIN,
L. C. HARDIN.
